UNITED STATES PATENT OFFICE.

HARVEY B. LINDSAY, OF OAKLAND, CALIFORNIA, ASSIGNOR TO DRY ZERO CORPORATION, OF WILMINGTON, DELAWARE, A CORPORATION OF DELAWARE.

MATTRESS MACHINE.

Application filed May 14, 1925. Serial No. 30,393.

To all whom it may concern:

Be it known that I, HARVEY B. LINDSAY, a citizen of the United States, residing at Oakland, in the county of Alameda and State of California, have invented a new and useful Improvement in Mattress Machines, of which the following is a specification.

My invention relates to improvements in machines for forming bodies composed of a casing or covering, as for example, of cloth fabric, and filling located therebetween formed of separate fibres, and more particularly to bodies, such for example, as thermal-insulating bodies, or cushioning bodies such as bedding-mattresses, the filling of which is of relatively soft material, as for example, kapok, and extends in the casing in relatively loose or fluffy condition, as for example, in the case of kapok in such a condition as is produced by providing approximately one pound of the kapok to each cubic foot of space filled thereby.

Considerable difficulty has heretofore been presented in the securing together at the edges of such mattress-bodies, the sheets of casing material disposed at opposite faces of the filling in a position in which they cap one of the sheets without unduly distorting the filling, or producing waves in the sheets of casing material due to the fact that the filling is relatively yielding and presents slight resistance only to forces tending to distort it in a direction crosswise of its length.

One of my objects is to provide improvements in machines of the general character stated to the end that the edges of the sheets of casing material will be turned, or folded, to form closures at the opposite lateral edges of the casing, and in such condition stitched, without unduly distorting the mass of filling crosswise of its length, especially when the filling is in relatively soft fluffy condition, as for example, where it is composed of kapok; or producing waves in the sheets of casing material; whereby the finished body will be of substantially the same width throughout its extent as the mass of filling as produced in the former.

Another object is to provide a relatively compact construction of folder; to provide a construction of folder adapted for adjust-

ment to meet varying conditions presented by the filling and the casing material; and generally, to so improve upon machines of the general character above stated, that an improved product will be produced thereby.

Referring to the accompanying drawings:

Figure 1 is a plan view of a machine in which my improvements are incorporated. Figure 2 is a broken plan view of one edge portion of the machine with certain parts broken away. Figure 3 is an enlarged plan view of one of the two similar turning, or folding, devices forming parts of the machine of Figs. 1 and 2. Figure 4 is an enlarged section taken at the line 4 on Fig. 2 and viewed in the direction of the arrow 70 with the body being formed, omitted. Figure 5 is a view like Fig. 4 showing the adjacent portion of the body being formed. Figure 6 is a broken cross-sectional view of an edge portion of the completed body. Figure 7 is a section taken at the line 7 on Fig. 1 and viewed in the direction of the arrow; and Figure 8, a section taken at the line 8 on Fig. 1 and viewed in the direction of the arrow 80

While my invention is applicable to a variety of machines of the general character stated, I have chosen to illustrate it in a machine of the general character disclosed in my pending application for U. S. patent Serial No. 1509, filed January 9th, 1925, a brief description of certain features of which is included in the following description.

The machine shown is formed of an outwardly flaring section 10 affording a similarly flaring passage therethrough which opens at the smaller end 11 of the section 10 into a conduit 12 which leads from a source (not shown) of the fibre material, as for example, kapok, the fibres of which are in loose condition, and through which conduit the fibres are forced, as by air pressure into and through the passage in the section 10. The side walls of the section 10, which are spaced apart at the discharge end of this section, a distance corresponding substantially to the width of the body to be produced, extend, as represented at 13, beyond the top and bottom walls 14 and 15, respectively, of the section 10 and through

a former-device 16, the upper and lower parallel walls of which represented at 17 and 18, respectively, and apertured at 19 and 20 to permit of the escape of the fibre-trans-
5 porting air, extend laterally beyond the side wall extensions 13 and are vertically spaced therefrom as shown at 21 and 22, the same vertical spacing being provided between the upper and lower walls 14 and 15 of the con-
10 duit 10 and the opposing upper and lower walls 17 and 18 of the former-device 16 (Fig. 8). The ends of the upper and lower wall portions 17 and 18 of the former 16 are connected together, beyond the side wall
15 portions 13, by end walls 23, whereby the front and rear portions of the former 16 are open to receive the filling and casing material from which the body is to be formed, and permit of the passage of the
20 same therethrough.

At a point in advance of the former-device 16 the machine is provided with rolls 24 and 25 of the material to form the casing, these rolls being supported above and
25 below, respectively, the section 10, with the free ends of the rolls extending into the former 16 through the space between the walls 14 and 15 and the walls 17 and 18, and between the last-referred-to walls and
30 the filling fed into the former and represented at 26, which filling is continuously fed to the former 16 as the filling and casing material is drawn therethrough, as hereinafter described, the filling 26 filling the
35 space between the sheets 24 and 25 of the casing material and the end walls 13 extending into the former 16.

Beyond the former the machine is provided with stitching mechanisms comprising
40 a plurality of stitchers 27 carried by the frame of the machine and operated through the medium of a driving shaft common thereto and driven from any suitable source. The stitchers 27 may be of any desirable
45 construction, such as are commonly used in the manufacture of stitched pads of various kinds, and are operated in any desirable manner to produce lines of stitching through the body composed of the filling
50 26 and the sheets 24 and 25 of casing material, these lines of stitching extending parallel with each other and in a direction lengthwise of the body being formed.

The stitchers 27 at each end of the series
55 thereof, and which are provided to stitch through the lateral edge portions of the filling and the casing material, are arranged substantially in line with feed rollers journaled on the frame of the machine to ex-
60 tend crosswise thereof and above and below the plane of the formed body and so spaced apart vertically that the former body interposed therebetween is fed, in the operation of the rollers, in the direction of the
65 arrow in Fig. 1. One only of the rollers

referred to, namely, the uppermost one thereof, is illustrated in the drawings, this roller being indicated at 29 and driven in any suitable manner as through the medium of the belt pulley 31 thereon.

Interposed between the former 16 and the stitchers 27, and disposed at opposite sides of the machine, are devices, represented generally at 32 for engaging those edges of the sheets 24 and 25 of casing material which extend laterally beyond the end walls 13 of the section 10, and folding these edge portions upon themselves to overlie the intermediate portion of the upper sheet 24 of casing material preparatory to stitching
70 these edge portions in place by the end ones of the stitchers 27, these devices each comprising a turning, or folding, member represented generally at 33 and shown as formed of sheet metal and having an extension 34
75 at its lower edge which fits flatwise against a part of the stationary frame of the machine, to which latter the device 33 is secured as by the screws 35. Each member 33 is formed to present two plate portions 36 and 37, each of angle shape as shown and spaced apart preferably uniformly throughout their extent, as represented, these plate portions extending at their upper, horizontal, portions 38 and 39, respectively, toward the center of the machine as shown and connected together at their inner edges, as represented at 40, it being preferred that each of the members 33 be formed from a sheet of metal bent into the form described
80 and shown. The lower edges of the vertical portions 41 of the inner plate members 36, which latter form guides for the casing material 24 and 25, are spaced apart a distance
85 substantially equal to the distance between the side walls 13 plus double the thickness of the casing material, or, in other words, these vertical portions 41 extend in slightly outwardly offset position relative to the side walls 13, the extreme lower edges of the portions 41 of the guide member 36 extending above the under side of the sheet 25 of casing material, a distance equal to substantially twice the thickness of the sheets of the casing material, as shown in Figs. 4
90 and 5. The upper horizontal portions 42 of the members 36 extend above the extreme lower edges of the vertical portions 41, a distance slightly less than the combined thickness of the filling and the sheets of
95 casing material as produced in the former 16. By preference, the plate members 37 are spaced from the opposing portions of the plate members 36, a distance sufficiently more than twice the thickness of a sheet of
100 the casing material to allow free passage thereof therebetween, as shown in Fig. 5.

Cooperating with each of the turning, or folding, devices described, is a spiked wheel
105 43, journaled at shaft portions 44 in bear-

ings 45 mounted on a revolubly adjustable ring 46 carried by the upper plate member 37, the plates 37 having clamping bolts 47 which extend through arcuate slots 48 in the rings 46, to permit of revoluble adjustment of the latter and the securing of these rings in such adjusted position. The spiked wheels 43, the spikes of which arranged in a circumferential series about the rim portions of the wheels, are represented at 49, project downwardly through openings 50 in the horizontal portions 39 of the plates 37, and the spikes 49 project into recesses formed in the upper surfaces of the horizontal portions 38 of the plates 36, by striking the metal of the portions 38 downwardly, as represented at 51.

In the beginning of the operation of the machine, the operator grasps the lateral edges of the sheets 24 and 25 of the casing material after the free ends thereof pass beyond the former-device 16 and inserts them into the angle shaped guideways provided between the plates 36 and 37 at opposite sides of the machine, to the position illustrated in Fig. 5, positioning these free edges beneath the spiked wheels 43 at the opposite sides of the machine, the spikes at the lower portions of which penetrate both thicknesses of the casing material at the upper face of the body being formed; and thereupon draws the free end of the partially formed body into a position in which the body becomes positioned to be acted upon the stitchers 27, and then by the feeding device of which the rollers 30 are parts, it being understood that feed of the fibre filling continues during this operation, for continuing the forming of the mass of filling in the former 16 between the sheets 24 and 25 of casing material, the machine thereafter automatically operating to continue the forming, edge-turning and folding and stitching and feeding operations referred to.

In the movement of the body being formed the free edges of the casing material are automatically turned, or folded, to a position in which they are superposed upon the intermediate portions of the sheet 24, as shown in Fig. 5 as to the edge portions of the sheets 24 and 25 along one side of the body being formed, by the conjoint action of the turning, or folding, devices 33 and the spiked wheels 43, the axes of which latter diverge in a direction away from the former 16 which causes these wheels to rotate by the turning force exerted against them in the feed of the body being formed through the machine, as stated, to exert a constant pull on the free edges of the casing material engaged by the spikes of these wheels, from opposite sides of the machine toward the center thereof, it being understood that the degree of pulling force exerted by the wheels depends on the angle at which their axes of

rotation extend relative to the line of travel of the body being formed. By properly rotatably adjusting the rings 46 carrying the wheels 43, and by drawing the lower sheet 25 of casing material sufficiently taut 70 crosswise of the length of the body being formed, in the preliminary positioning of the edges of the casing material in the turning, or folding, members 33 and into engagement with the spiked wheels 43, as 75 above stated, the desired tension on the edges of the casing material may be exerted for folding them to the position shown in Fig. 5 and causing them to extend in smooth condition from edge to edge of the formed 80 body.

The side edges of the sheets 24 and 25 of casing material having been turned, as stated, the end ones of the stitchers 27, in the continued movement of the body 85 through the machine, stitch through the lower and upper sheets 24 and 25 of the casing material, the superposed turned edges of this material and the filling 26, as indicated, as to one edge of the body, at 52 90 in Fig. 6, to close the casing along the side edges of the mattress body.

It will be observed that by providing the vertical portions 41 the sheet 25 is drawn against the lower edges of this portion 95 which projects the adjacent edges of the filling 26 against exertion of force by the sheet 25 in the turning, or folding, operation and thus the edges of the sheets 24 and 25 are turned, or folded, as stated without 100 compacting the filling crosswise of the body being formed and both sheets are caused to be in smooth condition.

It will be noted that by providing the recesses 51 in the plates 36 the spikes 49 are 105 permitted to penetrate both layers of the casing sheets located between the plates 36 and 37 to effect a draining action on both of the sheets (these sheets not curving downwardly into these recesses because they are 110 drawn taut), but are prevented from penetrating those portions of the sheets which cover the filling and extend directly beneath the plates 36 which penetration would occur if the plates 36 were slotted instead of being 115 merely recessed as stated and in the event of such penetration would interfere with the proper operation of the spiked wheels.

While I have illustrated and described a particular embodiment of my invention and have shown it as incorporated in a particular type machine, I do not wish to be understood as intending to limit it thereto as various modifications and alterations may be made in the structure shown, and the 120 same incorporated in other types of machines without departing from the spirit of my invention.

What I claim as new, and desire to secure by Letters Patent, is:

in the direction of movement of said filling and sheets through the machine.

10. In a machine of the character set forth, the combination with a former in which filling material extends between spaced sheets of casing material and is fed therethrough, of means for folding the edge-portions of said sheets beyond said filling into a position in which they flatwise oppose one of said sheets, comprising inner and outer guide-members of angle shape and spaced apart, said inner guide-members extending at certain portions thereof along the side surfaces of said filling and at other portions along the upper surface of said filling and against which inner guides said edge-portions of said sheets are folded.

11. In a machine of the character set forth, the combination with a former in which filling material extends between spaced sheets of casing material and is fed therethrough, of means for folding the edge-portions of said sheets beyond said filling into a position in which they flatwise oppose one of said sheets, comprising inner and outer guide-members of angle shape and spaced apart, said inner guide-members extending at certain portions thereof along the side surfaces of said filling and at other portions along the upper surface of said filling and against which inner guides said edge-portions of said sheets are folded, and means engaging said edge-portions of said sheets for drawing them toward each other.

12. In a machine of the character set forth, the combination with a former in which filling material extends between spaced sheets of casing material and is fed therethrough, of means for folding the edge-portions of said sheets beyond said filling into a position in which they flatwise oppose one of said sheets, comprising inner and outer guide-members of angle shape and spaced apart, said inner guide-members extending at certain portions thereof along the side surfaces of said filling and at other portions along the upper surface of said filling and against which inner guides said edges of the sheets are folded, and spiked wheels rotatably mounted on those portions of said outer guide-members which oppose the upper surface of said filling in a position in which their spikes engage said folded edge-portions of said sheets, the axes of said wheels diverging in the direction of movement of said filling and sheets through the machine, the lower edges of said guide members extending adjacent the lower face of said filling.

13. In a machine of the character set forth, the combination with a former in which filling material extends between spaced sheets of casing material and is fed therethrough, of means for folding the opposed edge-portions of said sheets beyond

said filling at each side of the latter, into a 65 position in which they flatwise oppose each other and lap one of said sheets, comprising guide-members having portions which extend along the sides and upper surfaces of said filling with their lower edges adjacent 70 the lower face of said filling, and spiked wheels rotatably mounted in a position in which their spikes penetrate both of said sheets at the portions thereof flatwise opposing one sheet thereof, as above stated, at 75 both lateral edges of said filling, the axes of said wheels diverging in the direction of movement of said filling and sheets through the machine.

14. In a machine of the character set forth, the combination with a former in which filling material extends between spaced sheets of casing material and is fed therethrough, of means for folding the opposed edge-portions of said sheets beyond 80 said filling at each side of the latter, into a position in which they flatwise oppose each other and lap one of said sheets, comprising guide-members having portions which extend along the sides and upper surfaces of 85 said filling with their lower edges adjacent the lower face of said filling, and spiked wheels rotatably mounted in a position in which their spikes penetrate both of said sheets at the portions thereof flatwise opposing one sheet thereof, as above stated, at 90 both lateral edges of said filling, the axes of said wheels diverging in the direction of movement of said filling and sheets through 95 the machine, and means for stitching the 100 folded edge-portions of said sheets to the sheet which they lap.

15. In a machine of the character set forth, the combination with a former in which filling material extends between 105 spaced sheets of casing material and is fed therethrough, of means for folding the opposed edge-portions of said sheets beyond said filling at each side of the latter, into a position in which they flatwise oppose each other and lap one of said sheets, comprising 110 guide-members each formed of spaced apart inner and outer guide forming plates of angle shape presenting an angular channel therebetween, portions of each of said plates extending along the adjacent edge of said filling and other portions extending along the upper surface of said filling at its edge-portions, said portion of said outer plate extending along the upper surface of said filling containing an opening and the opening portion of said inner plate containing a depressed portion presenting an upwardly-opening recess directly below said opening, and a spiked wheel revolvably mounted 120 on said outer plate to extend downwardly through said opening therein and at its spikes into said recess, the axes of said 125

wheels diverging in the direction of movement of said filling and sheets.

16. In a machine of the character set forth, the combination with a former in which filling material extends between spaced sheets of casing material and is fed therethrough, of guide means adapted in the feeding of said filling and sheets to engage the edge-portions of said sheets beyond said filling and turn said edge-portions into a position in which they lap one of said sheets, and spiked rollers rotatably supported to engage at their spikes with the folded edge-portions of said sheets, their axes diverging in the direction of movement of said filling and sheets through the machine, said wheels

being adapted for bodily adjustment to vary the angle at which they diverge.

17. In a machine of the character set forth, the combination with a former in which filling material extends between spaced sheets of casing material with edge-portions thereof extending beyond the sides of said filling, and in such condition is fed through said former, of means operating in the movement of said sheets to fold the projecting edge-portions of said sheets into a position in which they lap one of said sheets, and means for stitching said folded portions to the sheet lapped thereby. 25

HARVEY B. LINDSAY.
